UNITED STATES PATENT OFFICE

123,685

DESIGN FOR A TOY ANIMAL

Ivan Sokoloff, Boston, Mass.

Application September 14, 1940, Serial No. 95,047

Term of patent 14 years

To all whom it may concern:

Be it known that I, Ivan Sokoloff, a citizen of the United States, residing at Boston, in the county of Suffolk and State of Massachusetts, have invented a new, original, and ornamental Design for a Toy Animal, of which the following is a specification, reference being had to the accompanying drawing, forming part thereof.

animal embodying my new design, the opposite side being substantially the same as that illustrated;

Figure 2 is a view in front elevation.

I claim:

The ornamental design for a toy animal, as shown and described.

IVAN SOKOLOFF.
